NONREFILL BOTTLE VALVE

Gerald Cahill, Chicago, Ill.

Application May 3, 1937, Serial No. 140,505

13 Claims. (Cl. 215—23)

This invention relates to a non-refillable bottle.

Several methods are practiced in attempting to fill such bottles. For example, a wire may be inserted into the bottle neck in an effort to hold the valve open while the bottle is filled; or the bottle may be given rapid oscillating or reciprocating movements while submerged in a liquid.

An object of the invention is to provide an improved bottle from which liquid contained therein may be easily poured out, but which cannot be filled again by any method known.

Another object is to provide a structure having improved means for obstructing opening of the valve when the bottle is given a reciprocating movement. A further object is to provide a structure in which the valve is locked in closed position during shipping and storage.

Another object is to provide means by which the guard structure is irretrievably locked in the neck of a bottle. Still another object is to provide improved means for releasably engaging the valve lifting means with the valve. Other specific objects will appear as the specification proceeds.

The invention is illustrated, in preferred embodiments, by the accompanying drawings, in which—

Fig. 1 is a vertical sectional view of a bottle neck equipped with my improved means for preventing refilling, the structure being shown in normal upright position with closure attached; Fig. 2, a view similar to Fig. 1, but showing the apparatus with closure removed and in inverted or pouring position; Fig. 3, a view similar to Fig. 2, but showing the apparatus after it has been given a quick reciprocating movement; Fig. 4, a detail plan view of a top plate employed in forming the top wall of the guard structure; Fig. 5, a detail plan view of the lower plate employed in forming the top wall of the guard structure; Fig. 6, a detail view of the locking piece at the top of the guard structure, the view being taken as seen from the bottom of the locking piece; Fig. 7, a detail side elevational view of the locking piece shown in Fig. 6; Fig. 8, a transverse sectional view, showing the ring carrier member and taken as indicated at line 8 of Fig. 3; Fig. 9, a transverse sectional view taken as indicated at line 9 of Fig. 3, the position of the weight slide when the bottle is inverted being shown in dotted lines; Fig. 10, a detail side elevational view of the upper weight member; Fig. 11, a detail plan view of the slide which is associated with the weight member; Fig. 12, a detail side elevational view of the nut employed in locking the guard

structure within the container neck; Fig. 13, another detail view of the nut shown in Fig. 12, this view being taken as seen from its under side; Fig. 14, a detail elevational view of the ring carrying member; Fig. 15 is a plan view showing the clamping ring for locking the guard against withdrawal from the container neck; Fig. 16, a broken vertical sectional view of a modification, this view showing the parts in normal or upright position; and Fig. 17, another broken vertical sectional view of the modification shown in Fig. 16, this view showing the structure in inverted or pouring position.

As illustrated in Figs. 1 to 15, A designates a container neck; B, a valve-equipped guard structure within the container neck; and C, means for irretrievably securing the guard structure within the container neck.

The container neck A may be of any suitable type adapted for receiving within it the guard structure. Neck A is provided, preferably near its base, with a constriction 10, against which the guard structure may be locked in place. At its top, the neck may be provided with ridges 11 with which the edges of cap 12 engage. A lower cap 13 is pressed downwardly by cap 12 and has its edges spaced from the neck edge by a resilient washer 14. At its central portion, plate 13 is struck downwardly for engaging with the locking piece of the guard structure.

The guard structure B includes an outer tube 15 and an inner tube 16. Outer tube 15 is provided with diametrically opposed slots or openings 17 and is crimped to provide a threaded portion 18. At its lower portion, outer tube 15 has an inturned portion 19, which forms a seat for the base 20 of inner tube 16. Tube 16 has its walls spaced from outer tube 15 and is provided with the diametrically opposed slots or openings 21 which are 90° removed from slots 17, as shown more clearly in Fig. 9 of the drawings. At the upper portion of tube 16 is an internal annular groove 22 which is engaged by the guard ring later to be described. Extending over the extreme top edge of tube 16 is a top wall 23 which is held secure by the top edge 24 of tube 15 being peened over on top of it. Wall 23 is comprised of a top plate 25, shown in detail by Fig. 4, having arcuate openings 26, and a lower plate 27, shown in detail by Fig. 5, having arcuate openings 28 registering with openings 26. Lower plate 27 is provided also with downwardly struck fingers 29 which form a socket for the ball of the pendulum later to be described.

A bell-piece 30 is fixedly secured to the bottom

edges of inner and outer tubes 15 and 16. The exterior walls 31 of piece 30 are frusto-conical in shape and at their bottom provide a seat 32 for the locking ring 35. The bottom of piece 30 is spider-like and has a central aperture 34 which receives the cord 35 holding the ball weight 36.

At the upper portion of bell-piece 30 is a short cylindrical passage or opening 49 into which is fitted the valve member 37. Member 37 is open at its bottom and is provided with openings 38 in its sides. Above member 37 is a float 39 having its edges extending beyond the edges of opening 49 and being attached to member 37 by means of bolt 48 which has an eyelet nut 41 at its lower end into which cord 35 is secured and has an eyelet head 42 for engagement with the valve stem 43. Valve stem 43 is formed of two diameters; the upper portion 45 is of larger diameter and the lower portion 46 is of a smaller diameter providing a shoulder 47 at the junction of these portions. The lower end of the stem has a hook 48 which engages with the eyelet head 42.

A weight member 50 of general cylindrical form, and as shown in detail by Fig. 10, is slidably disposed within tube 16 and above float 39. It is provided with exterior ridge portions 51 which engage the walls of tube 16, and has a central longitudinal opening 52 through which the valve stem 43 extends. On each side of weight member 50 are the diametrically opposed longitudinal grooves 53 which are adapted to slidably receive the cam bars 54 and 55 secured to the walls of inner tube 16. Cam bar 54 has a cam surface 56 near its lower end, and cam bar 55 has a cam surface 57 near its upper end. Near the top edge of weight member 50 is a transverse slot 58 through which a latching slide 59 extends. Slide 59, shown more clearly in Fig. 11, is provided with a central opening 60 having a larger portion 61 and a smaller portion 62.

When weight member 50 is in its downward position within the guard structure as shown in Figs. 1 and 3, the cam surface 56 of cam bar 54 is in engagement with one edge of latching slide 59 and causes the slide to assume a position in which the smaller portion 62 of valve stem 43 is engaged by the smaller portion 61 of opening 60. However, when weight member 50 is raised within the guard structure as in the position shown in Fig. 2, the cam surface 57 of cam bar 55 is in engagement with the other edge of latching slide 59 and causes the slide to assume a position in which the valve stem is received through the larger portion 61 of opening 60, and the larger portion 45 of the valve stem may pass freely through this opening.

Above weight member 50 and slidably disposed in tube 16 is the guard ring carrier 70, shown in detail by Fig. 14, having a central opening 71 and a flared upper portion 72. A guard ring 73 carried by ring carrier 70 is of substantially the same outer diameter as is the diameter of the inner surface of tube 16, and is slidable laterally of the carrier 70. A holding ring 74 may be employed to hold the guard ring to the carrier.

A pendulum 80 is pivotally mounted at the top of the guard structure directly above the valve stem 43 and when in position aligned with stem 43 is effective in preventing the valve from raising. At its upper end pendulum 80 is equipped with a ball 81 which is received into the socket formed by fingers 29 of the plate 27. Thus the pendulum is pivotally held and is allowed to swing in any direction. As shown in either of Figs. 1 to 3, pendulum 80 has two enlarged por-

tions. Its extreme bottom end is enlarged at 82, so as to be more effective in blocking upward movement of the valve stem. Also, it has the upper enlargement 83 which has the frusto-conical surface 84, the larger diameter of which is substantially the same as the diameter of opening 71 in carrier 70. The central portion 85 is of reduced diameter so that there will be no obstruction to the movement of the valve stem upon raising of the valve.

A U-shaped locking member 90 has its curved legs 91 extending through openings 26 and 28 in top wall 23 and engaging the flat top surface of enlargement 83 on pendulum 80. One of legs 91 has an enlargement 91a which prevents the member from being removed from top wall 23. It is readily seen that when member 90 is pressed downwardly the pendulum will be urged into a position aligned with valve stem 43 and in which it obstructs the opening movement of the valve.

For locking the structure within the neck of a bottle I provide means C, including the lower clamping ring 85, shown in detail in Fig. 15, which is placed about the bell-piece 30. Ring 85 is of the expanding type and is provided with the outwardly extending bends 86 adapted to engage the neck of the bottle. In assembling the structure within the neck A of a bottle, the ring 85 is first placed about the upper portion of bell-piece 30 and the whole structure pushed downwardly within the bottle neck until the ring 85 is well below the constriction 10. Then ring 85 expands and moves downwardly on bell-piece 30, finally resting on seat 32.

Packing material 87 is then inserted about the guard structure and the packing nut 95 screwed down on the packing material. Packing nut 95, as more clearly shown in Figs. 12 and 13, is formed with threads 96 which are adapted to engage with the threaded portion 18 of outer tube 15. At its bottom, nut 95 has an outwardly extending flange 97 which presses against packing material 87 as the nut is tightened. At its top, nut 95 is provided with ratchet teeth 98 each of which have one inclined surface and one square surface, so that they may be engaged for turning the nut down into locked position but cannot be engaged to unscrew the nut. Further means for preventing the unscrewing of nut 95 is provided in the spring fingers 88 so arranged that their ends will engage one of slots 17 in outer tube 15 when an attempt is made to turn the nut in a direction to loosen it.

When nut 95 has been tightened to press packing material 87 firmly against the top of constriction 10 and at the same time bring clamping ring 85 tightly against the bottle below the constriction, the guard structure B is irretrievably and absolutely locked within the neck A. A tool may be inserted into the bottle neck and outside the guard structure for engaging ratchet teeth 98 of nut 95 for tightening the nut, but obviously a tool could not engage these teeth for turning the nut to loosen it. It is also apparent that the lower clamping ring 85 cannot be loosened, for before this ring could be contracted it must move upwardly to the smaller diameter of the bell-piece 30, and this is impossible because of the engagement of bends 86 with the bottle neck.

In normal use the bottle is first filled with liquid; then the guard structure is inserted in the neck and locked in place as above described. During storage and shipment the cap 13 is attached to the top of the neck. With the cap in

place as shown in Fig. 1, the inner plate 13 urges locking member 90 downward which causes the pendulum 80 to be maintained in a position aligned with valve stem 43 to block the opening 5 movement of the valve. Thus while the container is being stored or shipped, the valve is maintained in a closed condition so that no liquid is allowed to enter the guard structure.

When the liquid within the bottle is to be used, 10 the cap 12 may be removed and the bottle inverted as shown in Fig. 2 to allow the liquid to pour out freely. As the bottle is inverted, gravity causes the pendulum 80 to swing to the non-obstructing position shown in Fig. 2, so that the 15 valve stem 43 is free to move forwardly. Also, the weight member 50 moves forward and causes the shoulder 47 of the valve stem to be caught at latching slide 59, so as weight 50 moves forward it positively raises float 39 and member 37.

20 (It will be remembered that when weight 50 was in lowered condition the cam 56 caused latching slide 59 to assume position for engaging shoulder 47.) With the valve thus raised, liquid may flow through openings 38 in valve member 37 and 25 enter the interior of inner tube 16. The liquid may then flow out through one of openings 21 to the space between tubes 15 and 16, and from here the liquid may pass out of the guard structure through one of openings 17 and drain from 30 the bottle neck. As the liquid passes outwardly through the guard structure the air may enter to take its place through the other openings in tubes 15 and 16.

When weight member 50 has moved forwardly 35 to its extreme position the cam 57 engages latching slide 59 and moves it to bring the larger portion 61 of opening 60 into register with opening 52 in the weight, so that stem 43 is free to move within opening 52 to allow the valve to close. 40 Thus unlatched from weight 50, the float 39 will retreat to close the valve if an attempt is made to force liquid upwardly into the neck while the container is still inverted. And if the container is turned to horizontal position, the weight 36 45 serves to pull the valve back to closed position.

In the normal pouring operation of the bottle, the ring carrier 70 will move forward until the guard ring 73 drops into groove 22 of the inner tube 16. In this position (Fig. 2) the opening 71 of the ring carrier is adjacent the smaller part 85 of the pendulum 80. However, when the bottle is given a rapid longitudinal oscillating movement, the ring 73 will skip past the groove 22 and allow the carrier 70 to move farther forward (Fig. 3). As this member moves farther forward, the flange 72 engages the conical surface 84 of enlargement 83 on pendulum 80 and causes the pendulum to be urged into a position aligned with valve stem 43, and this prevents 55 the valve from again being opened. Such prevents the filling of the bottle by a rapid oscillating movement while the bottle is submerged in a liquid.

The construction and operation of the modified form of the invention shown in Figs. 16 and 60 17 is identical with the preferred form just described except for the pendulum and carrier members. As shown in Figs. 16 and 17 the pendulum 80 is equipped with a ball 81^a held in 65 a socket at the top of the guard structure as in the preferred form. A stem 85^a of reduced diameter is provided at its bottom end with an enlargement 82^a and has secured to it a disk 83^a.

The carrier member 70^a is loose within tube 16 70 and is provided with an outwardly extending top

edge 73^a having an outer diameter substantially the same as the inside surface of inner tube 16. At its center, member 70^a has a conically shaped opening 71^a which receives through it the pendulum 80^a.

As the bottle is inverted in the ordinary operation of pouring, the carrier 70^a moves forward until edge 73^a drops into groove 22 of the inner tube 16. This holds the carrier against further forward movement and the pendulum remains in non-obstructing position. However, when the bottle is given a violent oscillating movement, the edge 73^a will slip past groove 22 and allow the carrier to move farther forward. As carrier 70^a moves farther forward it engages 15 one edge of disk 83^a and causes the pendulum to become aligned with valve 43, and so prevents the valve from opening again.

The foregoing detailed description has been given for clearness of understanding only, and 20 no unnecessary limitations should be understood therefrom, but the appended claims should be construed as broadly as permissible, in view of the prior art.

I claim:

1. In combination with a container neck, a guard structure locked within said neck and providing a flow passage, a float valve within said passage, said valve being equipped with a valve stem having a shoulder thereon, a weight slidably disposed within said structure, a latch member slidably attached to said weight and having an opening through which said stem is received, said opening having a smaller portion adapted to engage said shoulder and a larger portion 30 through which said shoulder may pass freely, cam means attached to said guard structure for moving said latch member to a position in which said smaller portion of said opening engages said stem when said container neck is in substantially 35 upright position, and cam means attached to said guard structure for moving said latch member to a position in which said larger portion of said opening engages said stem after said container neck is inverted to a pouring position. 40

2. In a guard structure for a container neck, said guard structure being equipped with a valve, a pivoted member controlling the opening movement of said valve, said member having a larger diameter and a smaller diameter, and a member 50 slidably disposed within said guard structure and having an opening therein through which said pivoted member is received, the smaller diameter of said pivoted member being normally adjacent 55 said opening, said slidably member being adapted to move to a position in which said larger diameter of said pivoted member is adjacent said opening and in which said pivoted member is maintained in valve-obstructing position when 60 the container is given a longitudinal reciprocal movement in upright position.

3. In a guard structure for a container neck, said guard structure being equipped with a float valve, a pivoted member controlling the movement of said valve, and a member slidably disposed within said guard structure and normally permitting said pivoted member to move into non-obstructing position, said member being adapted upon reciprocal movement of said container to move said pivoted member to valve-obstructing position, a groove within said guard structure, and a ring slidably carried by said slidably member, said ring being adapted normally to engage said groove to restrain said slidably 70 member, said ring being adapted to restrain said slidably member, said ring being adapted normally to engage said groove to restrain said slidably 75

member from moving said pivoted member to valve-obstructing position.

4. In a guard structure for a container neck, said structure being equipped with a float valve and having an internal groove, a pendulum pivotally supported in said structure and controlling the opening movement of said valve, and a member slidably disposed within said guard structure and normally permitting said pendulum to swing into non-obstructing position, said member being adapted to move forwardly into contact with said pivotal member and to urge said pivotal member into valve obstructing position when said container neck is given a longitudinal reciprocal movement, said slidale member being equipped with means for engaging said groove to restrain forward movement of said slidale member.

5. In combination with a container neck, a guard structure equipped with a float valve, a swingable member within said structure and controlling the movement of said valve, and means for irretrievably locking said structure within said container neck, said means including a threaded member having engaging means by which said member may be turned in only one direction.

6. In combination with a container neck, a guard structure equipped with a float valve, said structure having a slotted wall, a swingable member within said structure and controlling the movement of said valve, and means for locking said structure within said container neck, said means including a threaded member provided with a locking spring, said spring being adapted to engage a slot of said slotted wall to prevent turning of said member upon attempt to turn said member in a direction to loosen said guard structure.

7. In combination with a container neck having a restriction therein, a guard structure equipped with a float valve, a swingable member within said structure and controlling the movement of said valve, and means for locking said structure within said container neck, said means including an expanding ring engaging said container neck below said restriction and holding said structure against upward movement within said neck, and including also a threaded member securing said structure against downward movement within said neck.

8. Apparatus as set forth in claim 7 in which said ring is held in expanded condition by said structure and in which said ring can be contracted only after upward movement with respect to said structure.

9. In combination with a container neck having a restriction therein, a guard structure equipped with a float valve, a swingable member within said structure and controlling the movement of said valve from its seat, and means for locking said structure within said container neck, said means including an expanding ring carried in expanded condition by said structure, said ring engaging said container neck below said restriction and adapted to prevent upward movement of said structure within said neck, packing material within said neck and above said restriction, and a threaded member adapted to engage said structure for pressing said packing material against said restriction and securing said structure against downward movement within said neck.

10. In combination with a container neck, a guard structure locked within said neck and comprising an inner tube and an outer tube spaced from said inner tube, each of said tubes having diametrically opposite openings therein, the openings in said outer tube being 90° removed from the openings in said inner tube, said structure being equipped with a float valve, a swingable member within said tubes and controlling the movement of said valve, and means for locking said structure within said container neck, said means including a threaded member engaging said outer tube.

11. In combination with a container neck, a guard structure locked within said neck and providing a flow passage, a float valve within said passage and controlling the flow therethrough, a weight slidably disposed within said guard structure, said weight being adapted to releasably lift said valve to allow flow through said passage when said container neck is inverted to pouring position, a pivoted member normally obstructing the opening movement of said valve but adapted to move to non-obstructing position when said container neck is inverted to pouring position, and means for again moving said pivoted member into valve-obstructing position when the container is given a longitudinal reciprocal movement.

12. In combination with a container neck having a constriction therein, a valve and guard structure within said neck and passing through said constriction, mechanism for preventing the removal without destruction of said valve and guard structure from said neck, said mechanism including means carried by said structure above said constriction and engaging the same so as to prevent said valve and guard structure from being pressed into the container, and means carried by said structure and engaging said container neck below said constriction for preventing upward movement of said structure, said last-mentioned means comprising a bell-shaped structure and a resilient ring slidably carried by said bell-shaped structure, said bell-shaped structure being provided with a shoulder for supporting said resilient ring in its lowermost expanded position.

13. In combination with a container having a neck portion and a container portion, said neck being constricted near its base and widening into the said container, a guard and valve structure within said neck, mechanism for locking said structure within said neck against removal therefrom either in an upward direction or in a downward direction without destruction of said neck, said mechanism including shoulder means carried by said guard structure and engaging said neck above said constriction for preventing downward movement of said guard structure, a locking structure extending below said constriction, said structure being bell-shaped and having a widened lower portion, threaded means engaging and associated with said locking structure and said guard structure for raising and lowering said locking structure through a limited range, and a resilient ring slidably supported by said bell-shaped structure and adapted to be expanded below said constriction for preventing upward movement of said guard and valve structure.
